UNITED STATES PATENT OFFICE.

JAMES D. WOLF, OF CROTON-ON-HUDSON, NEW YORK.

FIRE-FIGHTING APPARATUS.

1,418,505.

Specification of Letters Patent. Patented June 6, 1922.

Application filed April 22, 1921. Serial No. 463,444.

To all whom it may concern:

Be it known that I, JAMES D. WOLF, a citizen of Hungary, residing at Croton-on-Hudson, in the county of Westchester and 5 State of New York, have invented certain new and useful Improvements in Fire-Fighting Apparatus, of which the following is a specification.

This invention relates generally to fire 10 fighting apparatus, having more particular reference to an extensible ladder and platform device.

The invention has for an object to provide a novel device of this kind which can be 15 readily raised or lowered and which may be used as a ladder to gain access to the upper floors of burning buildings, and also provides a platform from which a stream of water may be directed into the windows on 20 such upper floors.

For further comprehension of the invention, and of the objects and advantages thereof, reference will be had to the following description and accompanying drawings, 25 and to the appended claim in which the various novel features of the invention are more particularly set forth.

Fig. 1 of the drawings is a plan view of 30 my improved device showing it carried upon a motor truck, and in raised position, the clutch operating mechanism being omitted.

Fig. 2 is a side view thereof, the drums carrying the ladders being shown in transverse section.

Fig. 3 is a fragmentary perspective view 35 showing the manner in which the ladder rounds are arranged with reference to each other when the ladder elements are wound upon the drums.

Fig. 4 is a fragmentary vertical section 40 of one of the ladder elements.

Fig. 5 is a detail perspective view showing the clutch through which the winding drums are connected to the motor, and the means 45 for automatically disengaging the winding drums from the motor.

Fig. 6 is a detail face view of one of the ladder elements extended.

Fig. 7 is a similar view to Fig. 2 but showing the device in lowered position.

I have here shown my device as carried upon a motor truck frame 10, being mounted to the rear of the driver's seat 11.

In carrying out the invention I provide a 55 pair of drums 12 and 13 respectively extending transversely of the truck and spaced

apart longitudinally of the latter, these drums being supported in suitable bearing members carried on the truck frame. These drums are adapted to have ladder elements 60 wound thereon, these ladder elements being indicated generally at 14 and 15 in Fig. 1 of the drawings.

The posts of these ladder elements are made up of a series of short bars 16 hinged 65 to one another by hinges 17 to abut end to end. The rounds 18 of the ladders are located midway between the ends of these bars 16. To hold the ladder posts against collapsing I provide on the sides thereof 70 spring rods 19 which are secured at one end to one bar or section and project freely at the opposite end across the round of the next section. Upon the upper ends of the ladder elements a platform 20 is mounted, pivotal 75 connections being provided between said ladder elements and the platform.

As seen in face view the ladders narrow in width toward the top, this construction being utilized to facilitate winding on the 80 drums, the posts winding in a spiral formation on the drums. The drums 12, 13 are of polygonal shape, each side corresponding in width to the length of one of the bars, or post sections, 16, while the outer edges of 85 these bars are longitudinally curved on lines which are concentric to the respective drums when the bars are engaged therewith.

When in lowered position, as in Fig. 7, the ladder elements are wound several turns 90 around the drums, and to permit of each succeeding turn lying close upon the periphery of each drum the rounds 18 are arranged as in Fig. 3, the higher ones being set further in from the hinged edges of the bars 16, 95 while notches 21 are provided in the bars in which the rounds of the preceding turns are received. The lower rounds are preferably arranged to project from the hinged edges of the posts and are received in notches 22 in the drums.

Partially surrounding the drums are segmental frame elements 25 carrying a series of rollers 26 which are adapted to engage the outer edges of the posts and act to bend 100 the latter against action of springs 19 around the drums.

The drums are adapted for rotation by the usual motor indicated at 27 which drives the truck, a sprocket chain 28 being looped 110 over suitable sprocket wheels on the main shaft of the motor and a second shaft 29 ex-

tending longitudinally of the truck. Upon this shaft 29 are fixed a pair of bevel pinions 30 meshing with a pair of bevel gears 31 fixed to the shafts of the drums.

5 The shaft 29 is formed in two sections adapted to be united by a clutch 35 of ordinary construction. This clutch is here shown as operable by a yoke arm 36 on a rock-shaft 37 on which is fixed a hand lever 38 provided with the usual slidable locking rod 39 connected to a bolt 40 adapted to engage a notched segment 41. To this rod 39 is pivotally connected one end of a lever 42 which is fulcrumed between its ends as at 15 43 to a suitable fixed part. A second lever 44 is pivotally connected at one end to the other end of the first lever and projects into the path of a lug 45 on one of the lower bars 16 to be engaged thereby and release the 20 clutch. A coiled tension spring 46, connected to the hand lever 38, acts to move the clutch to inoperative position when the rod 39 is raised.

The sizes of the drums 12 and 13 are preferably so proportioned relatively that the ladder element 14 near the front of the truck will raise vertically, and the other ladder element 15 at an inclination toward the first ladder element.

30 The manner of operation is as follows: Assuming the device to be in the raised position shown in Figs. 1 and 2, the ladder elements will be held against any tendency to collapse by the springs 19, which may be of 35 sufficient strength for this purpose; access to the platform 20 being preferably had by way of the inclined ladder element 15, the rollers 26 preventing the ladder elements disengaging from the drums at their lower 40 ends.

To lower the device the hand lever is

moved to set the clutch 35, causing the drums to rotate and winding the ladder elements thereon, the springs 19 being bent by engagement of the bars 16 with the rollers 26. 45 As the device lowers, each succeeding turn on the drum lies within the preceding turn, the arrangement shown in Fig. 3 allowing each turn to lie in flat contact with the drum.

To raise the device the lever 38 is set by hand to engage the clutch, and the ladder elements are unwound from the drums, raising to the position shown in Fig. 2. When the lug 45 engages lever 44 the locking bolt 40 is raised, and spring 46 moves the clutch 55 to released position.

Having thus described my invention what I claim as new and desire to protect by Letters Patent of the United States is as follows:—

60 A device of the type described comprising a support, a pair of drums on said support, ladder elements comprising posts adapted to be wound on the respective drums said ladder elements having their posts comprising short bars hinged together along one side edge to abut end to end, springs holding said bars against swinging movement upon one another, said posts inclining toward one another from the base of each ladder element toward the top, and rounds mounted on said bars, the rounds on the upper bars being set further from the hinged side edges of the posts than the rounds on the lower bars, the upper bars having their 70 hinged side edges notched to register with the rounds on certain of the lower bars when said elements are wound on their respective drums.

75 In testimony whereof I have affixed my signature.

80 JAMES D. WOLF.
